UNITED STATES PATENT OFFICE.

EARL E. GOULD, OF BELVIDERE, ILLINOIS.

ICE-VELOCIPED.

SPECIFICATION forming part of Letters Patent No. 508,011, dated November 7, 1893.

Application filed July 29, 1893. Serial No. 481,905. (No model.)

To all whom it may concern:

Be it known that I, EARL E. GOULD, a citizen of the United States, residing at Belvidere, in the county of Boone and State of Illinois, have invented a certain new and useful improvement in Ice-Velocipedes, of which the following is a specification.

My invention relates to ice tripes, provided with runners in lieu of wheels; and it consists of certain new and useful features of construction and combinations of parts hereinafter fully described and specifically pointed out in the claims.

Referring to the accompanying drawings, which form a part of this specification, Figure 1 is an isometrical view of my improvement. Fig. 2 is an enlarged, detailed rear elevation of the same, having the back portion of the wheel-guard sectioned away. Fig. 3 is an enlarged, detailed view of parts for connecting the runners with the frame of the velocipede. Fig. 4 is a view of devices also for connecting the runners with the velocipede frame. Fig. 5 is an enlarged, detailed view, 25 of the parts illustrated in Figs. 3 and 4, also showing their points and modes of attachment. Fig. 6 is a section, at the dotted line X—X in Fig. 3, of parts there shown. Fig. 7 is an enlarged, detailed view of a portion of 30 the front runner and brake of the machine. Fig. 8 is a side elevation of a fragment of the wheel-rim and a driving sprocket and the lower end of a spoke thereof. Fig. 9 is a section, at the dotted line X'—X' in Fig. 8, of 35 parts there shown.

Like letters of reference indicate corresponding parts throughout the several views.

A are the rear runners of the velocipede. A' are bearings thereon.

B B' are parts of the frame of the machine. B² B³ and B⁴ are, respectively, a double clip and collars fast thereto.

C C' are connecting-rods, pivot-jointed, by their upper ends, to the collars B³ B⁴, on the part B', by means of lugs B⁵ B⁶ thereon and bolts C² C³ inserted therethrough, and also pivot-jointed, by their lower ends, to the bearings A', on the runners A, by means of bolts C⁴, inserted through the jaws C⁵ and eyes C⁶ thereon.

D are sockets, having longitudinal slots D' therein and pivot-jointed, by their upper ends,

by means of the jaws D² thereon and the bolts D³, to the lugs B⁷ on the clip B².

E are rods, inserted into and adapted to be 55 at freely slid in the sockets D, threaded their lower ends, and provided with lugs E' projecting through the slots D' in the socket D, to prevent the withdrawal of the former from the latter.

F are springs, coiled about the rods E and included endwise between the lower ends of the sockets D and the nuts F', which serve both as bearings for, and to increase the action of, said springs.

G, Figs. 3, 4 and 6, are bearings having holes G' G² therein, the former to enable the same to be rigidly clamped against the parts C', by means of the nut G³, and the latter—threaded interiorly—to receive and support the rods E 70 and the parts supported thereby.

H are driving sprockets, secured to the half-round tire H', of the wheel H², by means of screws H³. After being provided with sprockets H, the tire H' is in turn secured into the 75 counterpart grooved rim H⁴ of the wheel H².

I is the front runner of the machine, having a bearing I' thereon. The runner I is pivotally connected with the part I², of the velocipede, by means of a bolt I³ passed through 80 the same and the bearing I' thereon.

J is a lever pivot-jointed by the hole J' therein to the frame of the velocipede at J².

J³ is a lever pivot-jointed, at J⁴, to the handle-bar J⁵.

J⁶ is an arm connecting, by pivot-joints, the short arm of the lever J³ with the hole J⁷ in the lever J.

K is a brake, connected to the lower rear portion of the runner I, by means of a pivot K'.

K² is a short arm, connected by one end thereof with the rear portion of the runner I, by means of a pivot K³.

K⁴ is a short horizontal lever, secured by one end to the lever J, by means of a clamp K⁵.

K⁶ is a connecting arm having pivotal connections, at K⁷ K⁸, with the free ends of the short arm K² and lever K⁴.

K⁹ is a connecting-arm having pivotal connections, at K⁹ K¹⁰, with the free end of the 100 short arm K² and the brake K.

My improved tripes may be used upon either ice or snow. The rider propels and guides the same just as he would any other

velocipede. The devices that connect the runners of the triped with the frame thereof are so jointed, at their connecting points, as to allow the rear runners A to spread and the driving-wheel H² to descend until the sprockets H engage with the ice or snow over which the machine is to be propelled.

I claim—

1. In an ice-triped, the combination of the following elements: the frame B B', the wheel H² having driving sprockets H secured to the half-round tire H' thereof, the rear runners, the connecting-rods C C', the sockets D, the rods E and the springs F, when all of said parts are constructed, arranged and connected substantially as and for the purpose specified.

2. In an ice-triped, the combination of the following elements: the frame B B', the front runner I, the levers J J³, the handle-bar J⁵,

the connecting-arm J⁶, the brake K, the arm K², the lever K⁴, the connecting arms K⁶ K⁹, when all of said parts are constructed arranged and connected substantially as and for the purpose specified.

3. In an ice-triped, the combination of the following elements: the frame B B', the rear and front runners, the wheel H², the connecting-rods C C', the sockets D, the rods E, the springs F, the levers J J³, the handle-bar J⁵, the connecting-arm J⁶, the brake K, the arm K², the lever K⁴, the connecting-arms K⁶ K⁹, when all of said parts are constructed arranged and connected substantially as and for the purpose specified.

EARL E. GOULD.
